DETACHABLE FIXTURE SUPPORT AND
BRACKET

Roy S. Sanford, Oakville, Conn., assignor to The
Autoyre Company, Incorporated, Oakville,
Conn., a corporation of Connecticut

Application June 12, 1937, Serial No. 147,821

4 Claims. (Cl. 248—223)

This invention relates to a detachable fixture support and bracket and has special reference to a bracket permanently secured to a wall or other support for receiving in detachable engagement therewith a bath room fixture or like member without recourse to the use of tools.

More particularly, this invention relates to a wall bracket having a face plate spaced from the wall and provided with a slot therein and a fixture having a bar secured thereto and extending therefrom and adapted to be inserted through the slot when the fixture and the bracket are angularly disposed relative to the normal assembled position thereof, there being means on the face plate frictionally engaging the inserted bar and predetermining the normal assembled position thereof. Also the invention contemplates the provision of a separate means on the face plate for engaging a portion of the fixture for locking the same in an assembled position.

It is desirable in a bath room fixture or like member to permit the same to be readily removed or interchanged at will without recourse to the use of tools. For example, in the provision of a soap dish it is preferable that the bottom of the dish be solid so as to prevent drippings from the wet soap falling on the floor or other surface below the fixture. Were a dish of this type to be permanently connected to the wall it would be difficult to clean. The present invention, therefore, contemplates a connection between the soap dish or other fixture and the wall bracket whereby the dish can be easily removed for cleaning or for any other purpose without disturbing the fixed relation between the bracket and the wall.

In the present invention the dish, which is used for illustrative purposes only, is disengaged from the bracket by merely turning the same approximately 90° so that the bar on the fixture will register with the slot of the bracket whereafter the bar may be removed therethrough. The fixture is engaged in the reverse order by inserting the bar through the registering slot and turning the same in the opposite direction until the bar rides up onto the indentations of the bracket to be locked thereby under friction.

In order to predetermine the assembled position of the fixture and bracket, other means as for example an indentation on the face plate, receives a portion of the fixture which in this instance is the peripheral extending edge thereof and a snap or locking action is obtained, the bracket being preferably made of spring steel to permit a distortion thereof prior to obtaining a

registration of the peripheral edge in the indentation.

Applicant is aware of constructions where a detachable engagement is had between a fixture and a wall bracket wherein a wedge-like binding is obtained to obtain the assembled relation therebetween. Unlike a wedge which will bind, depending upon the amount of pressure employed, the present invention locks and unlocks under the same or a uniform pressure. In the use of a wedge-like construction, sufficient pressure may be employed, resulting, for example, from the heavy weight of the fixture and supported object, to lock the fixture and bracket in such a relation that it is practically impossible to separate the same. In the present construction the weight of the fixture, or the fixture including its supported object, will not tend to lock the construction any tighter than it is ordinarily locked and the same pressure is employed in any event in either unlocking or locking the fixture and bracket into and out of an assembled position.

It is another feature of the present invention that there is no tendency for the fixture to unlock from the bracket after it has been assembled in subsequent handling, during shipment or on the store counter. It is usual either that the brackets and fixtures of the wedge type constructions are separately stored for counter use or there is a tendency for the bracket to become displaced from the fixture, either of which is undesirable. The present interlocking arrangement obviates both of the above objections. Further it will be noted that the locking arrangement is not seen when in assembled condition and this enhances the appearance of the construction.

One of the objects of this invention is to provide a device of the above type which is simple in construction, comparatively inexpensive to manufacture, and is durable.

Another object of this invention is to provide a device of the character indicated above which will have a pleasing appearance and yet be efficient in operation.

Other objects and advantages will hereinafter be more particularly pointed out and for a more complete understanding of the characteristic features of this invention, reference may now be had to the following description when taken together with the accompanying drawing, in which latter:

Figure 1 is a front elevational view of a con- 55

struction embodying the features of this invention;

Fig. 2 is a side elevational view of Fig. 1;
Fig. 3 is a rear elevational view of Fig. 1;

Fig. 4 is an enlarged vertical sectional view taken on the line 4—4 of Fig. 3, showing a portion of the dish broken away;

Fig. 5 is an enlarged vertical sectional view taken on the line 5—5 of Fig. 3, showing a fragmentary portion of the bracket and the supported dish;

Fig. 6 is a front elevational view of a modified form of bracket construction embodying the features of this invention; and

Fig. 7 is a vertical sectional view taken on the line 7—7 of Fig. 6.

Referring now to the drawing and more particularly to Figs. 1 to 5 inclusive thereof, a bracket 10 is adapted to be permanently secured to a wall or other support as by means of screws passing through apertures 11 in the face plate 12. The face plate 12 is provided with a peripheral flange 13 extending therearound to space the face plate from the wall or support to which the bracket is secured.

The face plate 12 is also provided with a raised portion 14 extending in a direction opposite to the direction of extension of the peripheral flange 13. The raised portion 14 is preferably substantially centrally disposed relative to the bracket proper and may be of any desired contour, the bracket 10 being of polygonal contour as well as the raised portion 14. However, it is to be understood that the specific contours employed are merely for the purpose of appearance.

An elongated slot 15 is provided in the raised portion 14 of the bracket and, in the instance shown in the drawing, the slot extends substantially horizontally. Ears 16 and 17 are provided on opposite sides of the slot 15 and preferably from the material of the slot, the slot being formed by slitting the material of the bracket at longitudinally and laterally spaced portions and bending the material therebetween at substantially right angles to the face of the bracket. The ear 16 is disposed near one end of the slot and the opposite ear 17 is disposed at the other end of the slot to provide stops, for a purpose which will hereinafter be more fully apparent.

A pair of projections 18 and 19 are deformed from the material of the raised portion 14 to extend in the direction of the wall or in a direction opposite to the direction of the raised portion. These projections are disposed on opposite sides of the slot 15 and are of the same height. The bracket 10 is preferably formed of spring steel in order to obtain a slight degree of resilience in supporting the projections 18 and 19, for purposes which will hereinafter be more particularly described.

The raised portion 14 is also provided with a pair of indentations 20 and 21 disposed adjacent the ends of the slot 15, the indentations extending in the direction of the projections 18 and 19 or in a direction toward the wall. The particular indentations shown are substantially V-shaped when viewed in cross section although, of course, they may be made of any shape that may be desired. The depth of the indentation is preferably not greater than the depth of the raised portion 14 and is preferably substantially less, so that the fixture, as will hereinafter be more fully apparent, will not rub against the face plate 12 in assembling or disassembling the fixture from the bracket.

The fixture disclosed for purposes of illustration is in the form of a soap dish 22 having a closed bottom 23 and grille-like side walls 24 having a continuous peripheral ledge 25 with a V-shaped face for receiving a square wire 26. 5 The wire 26 is preferably spot-welded to the ledge 25 and is of polygonal cross section principally for the purpose of appearance although, of course, it is to be understood that this cross section may be varied as desired. In keeping with the wire 10 26 of square cross section, the indentations 20 and 21 are V-shaped to receive the extending peripheral edge although the indentations 20 and 21 in any instance should be made to conform to the outline of that portion of the fixture that 15 extends for engagement therewith.

The fixture has a lateral extension 27 preferably welded, soldered, or otherwise secured to the wire 26 with a bar 28 extending at substantially right angles to the extension 27 and being 20 preferably formed integrally with or otherwise secured thereto intermediate the ends of the bar. The bar is adapted to be inserted through the slot 15 when the fixture and bracket are angularly disposed relative to the normal assembled 25 position thereof and, in the instance of the drawing, the bar 28 is shown as being perpendicular.

While the relation of the bar 28 to the fixture has been disclosed as being perpendicular with respect thereto it is, of course, to be understood 30 that the bar may be directed horizontally or at any other angle so long as the bracket and fixture are angularly disposed relative to the normal assembled position thereof at the time the bar 28 is 35 inserted through the slot 15. The bar 28 is 40 preferably of polygonal cross section providing a substantial engaging face along that portion facing the fixture, the flat face frictionally engaging the projections 18 and 19 when in an assembled position.

When the bracket 10 is permanently secured to a wall or other supporting structure and it is desired to assemble the fixture on the bracket, the fixture is moved to a position, in the instance shown in the drawing, where the length 45 thereof is vertical so that the bar 28 extends in a horizontal direction. In this position the bar which is substantially the size of the slot is inserted therethrough and the fixture moved to a position wherein the dish is horizontal. In 50 moving the fixture to this position the engaging face of the bar is moved into contact with the projections 18 and 19 which frictionally hold the fixture against displacement from the bracket. The ears 16 and 17 prevent a rotation beyond the 55 horizontal position of the dish and predetermine the assembled relation thereof. However, in order to lock the dish in such predetermined position, the indentations 20 and 21 permit the extending peripheral edge of the fixture to snap 60 therein. The resilience of the spring steel of the bracket permits of a tight engagement of the locking members.

When it is desired to disassemble the fixture from the supporting bracket the dish is moved 65 from its normal horizontal position to a vertical position for alignment of the bar with the slot so that the bar may be removed therethrough. It is necessary, in order to remove the dish, to force a disengagement of the square wire from the indentations 20 and 21 which is possible through the resiliency of the metal and to overcome the frictional resistance of the projections 18 and 19. Such positive locking prevents accidental displacement of the bracket from the fixture in 75

ordinary handling when in the store and when in ordinary use in the home. The extending peripheral edge of the fixture which engages the indentations 20 and 21 hide the slot, through 5 which the bar is inserted, from view and makes for a good appearance in the assembly.

In securing the bracket to the wall by means of screws extending through the apertures 11 thereof, the screws may be tightened to a greater 10 degree than is necessary and, in this manner, tend to lessen the resiliency of the spring material of the bracket. Therefore, it may be desirable to slit the material of the bracket as at 12a between the slot 15 and the apertures 15 11 to relieve the tension of the screws and retain at least the normal resiliency of the material of the bracket. It is to be understood, however, that it is not necessary to slit the material the entire distance to the apertures, or 20 in fact, to slit the material at all but it is desirable, nevertheless, to provide such a relieving means in many instances to guard against obtaining too great a tension on the bracket.

It may be desirable, in some instances, in order 25 to further enhance the appearance of the device, to hide the screws which hold the bracket to the wall or other supporting structure. By referring to Figs. 6 and 7 a bracket 29 is shown which is similar in all respects to the bracket 10 with the exception that no screw holes or 30 slits are shown in the face plate thereof, a backing plate 30 secured to the peripheral edge of the flange 31 being provided with screw holes 32 for receiving screws 32a.

The backing plate 30 is preferably formed of 35 metal, and fits within the flange 31 and is preferably spot-welded or soldered thereto. Screws are inserted through the holes 32 in the backing plate 30 and are accessible through the slot 40 33 which corresponds in the previous embodiment to the slot 15. In all other respects, however, the bracket is the same as that previously described and the fixture is mounted thereon in the same manner.

45 While but two embodiments of this invention are herein shown and described, it is to be understood that various modifications thereof may be apparent to those skilled in the art without departing from the spirit and scope of this invention and, therefore, the same is only to be limited by the scope of the prior art and the 50 appended claims.

I claim:

1. In a device of the character described, in

combination, a wall bracket having a face plate spaced from the wall and provided with a slot therein, a fixture having an extending peripheral edge and a bar extending therefrom and adapted to be inserted through said slot when said fixture and bracket are angularly disposed relative to the normal assembled position thereof, means on said face plate for frictionally engaging said inserted bar in a normal assembled position, and an indentation on said face plate for receiving said extending peripheral edge of said fixture for locking said fixture and said face plate in said normal assembled position. 5

2. In a device of the character described, in combination, a wall bracket having an apertured face plate spaced from the wall and provided with a slot therein, a fixture having a bar secured thereto and extending therefrom and adapted to be inserted through said slot when said fixture and bracket are angularly disposed relative to the normal assembled position thereof, said face plate having a slit extending outwardly from and communicating with said slot, and means on said face plate frictionally engaging said inserted bar in a normal assembled position. 10

3. In a device of the character described, in combination, a wall bracket having an apertured backing plate and having a face plate spaced from the wall and provided with a slot therein, a fixture having a bar secured thereto and extending therefrom and adapted to be inserted through said slot when said fixture and bracket are angularly disposed relative to the normal assembled position thereof, and means on said face plate for frictionally engaging said inserted bar in a normal assembled position, the apertures of said backing plate being accessible for receiving securing members through the slot in 35 said face plate. 40

4. In a device of the character described, in combination, a wall bracket having a face plate of spring material spaced from the wall and provided with a slot therein, a fixture having an extending portion and having a bar adapted to be inserted through said slot when said fixture and bracket are angularly disposed relative to the normal assembled position thereof, and an indentation on said face plate for receiving 45 said extending portion in snap engagement therewith for locking said fixture and said face plate in said normal assembled position. 50

ROY S. SANFORD.
